UNITED STATES PATENT OFFICE.

HEINRICH REUFER, OF STADTLOHN, GERMANY.

COMBINED DOBBY AND JACQUARD DEVICE.

SPECIFICATION forming part of Letters Patent No. 770,112, dated September 13, 1904.

Application filed June 1, 1903. Serial No. 159,645. (No model.)

To all whom it may concern:

Be it known that I, HEINRICH REUFER, a subject of the King of Prussia, Emperor of Germany, residing at 351 Vredenerstrasse, 5 Stadtlohn, in the Kingdom of Prussia and Empire of Germany, have invented a new and useful Combined Dobby and Jacquard Device, of which the following is a specification.

My invention relates to a combined dobbay 10 and jacquard device, the said dobbay being designed for the bindings of the ground and the jacquard device for the figure.

In the accompanying drawings, Figure 1 is a front elevation, Fig. 2 a horizontal section 15 on the line A B of Fig. 1, and Fig. 3 a vertical section on the line C D, Fig. 1, of this combined dobbay and jacquard device.

In carrying this invention into practice I provide the jacquard device as well as the dobbay 20 with a separate chain of cards or patterns K' and K². Both chains have, however, a common card-prism P' P², the prism P' for the jacquard-cards being larger than the prism P² designed for the dobbay-cards. The prism P' P² is 25 adapted to turn in a holder or support, which, as is known, consists of the two arms a' and a², fixed upon the shaft a³ and connected by a transverse rod a⁴, the said shaft a³ being arranged to swing in the side walls S S' of the 30 device. On one side the prism P' P² is provided in the known manner with a ratchet b, which as the prism holder or support swings outward is turned step by step through the agency of a pawl b⁴, pivoted to the side wall S'. 35 The prism P' P² is secured in its several positions by means of a spring-buffer b⁵, adapted to move in guides b' b⁵ on the arm a'.

The lifting bar or box T of the jacquard device has, for instance, six lifting-blades c'-6, 40 which in the upward movement raise the lifting-wires e'-6 not forced back by the needles d'-6 in accordance with the figure or pattern. By means of eyes or suspension-rods f' f² the lifting bar or box T is suspended from a carrier E, fixed in a slide T'. This slide is of T-shaped form, Fig. 2, and adapted to move up and down between two vertical guide-bars T², provided on the side wall S. The carrier E has prolongations E' and E², extending to 45 both sides. From the latter prolongation is

suspended the lever F for the blades of the dobbay, such lever being arranged to swing at the other end about a bolt g, which is fastened to the free end of an arm g', provided on the side wall S'. The articulated connection between the end E² of the carrier and the lever F is effected by a connecting-piece fixed to the latter and furnished with an eye F' for the end E² of the carrier E.

At their lower ends the lifting-wires h of the dobbay are connected with the rods i, which when the lifting-wires are lowered bear upon the board G² under the wires of the dobbay. The board G² of the dobbay is firmly connected with the board G' of the jacquard device, 65 and both boards together are fixed to a lever G³. This lever swings about a bolt G⁴ on an arm G⁵, fixed to the side wall S'. Thus both boards G' and G² are movable to enable, if necessary, a low shed to be formed. The 70 dobbay forms a high and low inclined shed; but the jacquard device forms a straight high shed and an inclined low shed, as indicated by dotted lines in Fig. 1.

The prism holder or support receives its 75 movement from a shaft I, driven in the well-known manner from the loom. This shaft is supported in the side walls S S', and fixed upon it at its end are arms j j', connected by a push-rod k or k' with the corresponding arm 80 a' or a² of the prism holder or support.

Upward and downward movement is imparted to the slide T', and thus to the lifting bar or box T of the jacquard device and to the lever F for the blades of the dobbay from 85 the shaft L. This shaft is supported parallel to the shaft I in the side walls S S', and secured upon it is a two-armed lever L' L², the arm L' of which is moved from the loom, while the other arm, L², acts upon the carrier 90 E by means of a push-rod L³. The boards G' and G² are likewise raised and lowered from the shaft L. A toothed sector M is arranged by the side of the lever L' on the said shaft. With this toothed sector engages a toothed 95 sector M', firmly connected with a lever M². This lever swings upon a bolt M³, fixed to the side wall S, and its free end takes by a roll M⁴ below a projection G⁴ of the board G'. Owing to the transmission through the toothed 100

sectors the lifting bar or box T, with the lever F, on the one hand, and the boards G' G² under the lifting-wires, on the other hand, make movements in opposite directions. Thus 5 either all these parts approach or recede from the position of rest at the same time.

The combination between the two machines consists in the following:

First. The card-prisms are combined into a 10 single card-prism, on which are the two sets of cards K' and K², arranged alongside of each other and each individually exchangeable.

Second. The lifting-wire boards G' G² are 15 fixedly connected with each other for the purpose of obtaining simultaneous movement common to both of them.

Third. The lifting-bar E of the jacquard-machine is connected with the lever F of the doby for the purpose of common ascent and 20 descent of same. This makes only one driving means necessary for the parts of both machines corresponding with each other in mode of operation.

In general the two machines work always 25 simultaneously. The doby works the ground and the jacquard-machine the pattern.

What I claim as my invention, and desire to secure by Letters Patent, is—

1. A combined doby and jacquard device 30 having a single card-prism, a chain of cards for the doby and another chain of cards for the jacquard device, substantially as and for the purpose herein set forth.

2. A combined doby and jacquard device 35 having a single card-prism, a chain of cards for the doby and another chain of cards for the jacquard device, a lifting-bar for the lifting-wires of the jacquard device, a carrier from which the lifting-bar is suspended, a slide 40 for holding the carrier, means for guiding this slide vertically, and means for moving the said slide up and down, substantially as herein set forth.

3. A combined doby and jacquard device

having a single card-prism, a chain of cards 45 for the doby and another chain of cards for the jacquard device a lifting-bar for the lifting-wires of the jacquard device, a carrier, from which the lifting-bar is suspended, a slide 50 for holding the carrier, means for guiding this slide vertically, means for moving the said slide up and down, a lever for the blades of the doby, and an articulated connection between this lever and the carrier of the lifting-bar, substantially as herein set forth. 55

4. A combined doby and jacquard device having a single card-prism, a chain of cards for the doby and another chain of cards for the jacquard device, a board for the lifting-wires of the doby and a board for the lifting-wires of the jacquard device, the said boards being firmly connected with each other, a lever for carrying both boards, and means for moving this lever up and down, substantially as herein set forth. 60

5. A combined doby and jacquard device having a single card-prism, a chain of cards for the doby and another chain of cards for the jacquard device, a lifting-bar for the jacquard device, a lifting-bar for the doby, an 70 articulated connection between the same, a board for the lifting-wires of the doby, a board for the lifting-wires of the jacquard device, the said boards being firmly connected with each other, a lever for carrying these 75 boards, a carrier for the lifting-bar, and means for simultaneously moving this carrier and the lever for the boards under the lifting-wires in opposite directions, substantially as herein set forth. 80

In testimony whereof I have signed my name to this specification in the presence of two subscribing witnesses.

HEINRICH REUFER.
